TAPE EMBOSsing TOOL

Arnold R. Bone, Needham, Mass., assignor to Dennison
Manufacturing Company, Framingham, Mass., a cor-
poration of Nevada

Filed Dec. 9, 1969, Ser. No. 20,425

Term of patent 14 years

Int. Cl. D18—99

U.S. Cl. D64—10

F/G. 1

FIG. 2

FIG. 3

FIG. 4

FIG. 1 is a front-side view in perspective of a tape embossing tool embodying the design;

FIG. 2 is a top plan view of the tape embossing tool of FIG. 1;

FIG. 3 is a side view in elevation of the tape embossing tool of FIG. 1, for which the undisclosed side has the same general appearance as FIG. 3; and

FIG. 4 is a rear view in elevation of the tape embossing tool of FIG. 1.

I claim:

The ornamental design for a tape embossing tool, substantially as shown and described.
